UNITED STATES PATENT OFFICE.

TRUMAN GARRAT PALMER, OF CHICAGO, ILLINOIS.

COPY-HOLDING DEVICE FOR TYPE-WRITERS.

SPECIFICATION forming part of Letters Patent No. 390,800, dated October 9, 1888.

Application filed May 1, 1888. Serial No. 272,431. (No model.)

To all whom it may concern:

Be it known that I, TRUMAN GARRAT PALMER, a citizen of the United States, residing at Chicago, in the county of Cook, State 5 of Illinois, have invented certain new and useful Improvements in Copy-Holding Devices for Type-Writers, of which I do declare the following to be a full, clear, and exact description, reference being had to the accompanying 10 drawings, forming part of this specification.

My present invention has for its object to provide an improved means whereby the copy-holder that sustains the manuscript or other matter to be copied may be brought directly in 15 front of the operator of the machine while being copied, and which may be readily moved to one side when it is desired to lift the carriage of the type-writer or to place the copy-holder temporarily out of use.

20 To this end my invention consists in the novel features of construction hereinafter described, illustrated in the accompanying drawings, and particularly pointed out in the claims at the end of this specification.

25 Figure 1 is a perspective view of a type-writer having my improvements applied thereto. Fig. 2 is a detail view, from the rear side, of one of the supports or clamps for holding the parts upon the type-writer, showing also 30 an adjacent portion of the bar. Fig. 3 is a view in central cross-section through the form of carrier illustrated in Fig. 1, the standard of the copy-holder and the set-screw being shown in side elevation. Fig. 4 is a detail perspective view of a modified form of my invention. Fig. 5 is a view in cross-section on line *x* of 35 Fig. 4.

A and A' designate the front corner-posts of the machine, which in the construction shown 40 is of the ordinary "Remington" or "caligraph" type, these posts being of angular shape, as shown. Upon the post A is attached the clamp or support B, which, in the construction shown in Figs. 1 and 2, consists of a simple U-shaped piece having a threaded perforation to receive the set-screw B', which serves 45 to securely retain the clamp or support B upon the post A in the position indicated in Fig. 1.

50 B' designates a clamp similar to that shown in Fig. 2, but by preference provided with a

somewhat longer set-screw, B³, that is provided also with a jam-nut, B⁴, the set-screw B³ serving to hold the clamp or support B' upon the post A', while the jam-nut B⁴ serves to securely retain in position the bar C, that extends across the front of the machine, this bar being provided at one end with a long slot, c, that fits over the set-screw B³, and being provided with the open transverse slot c', through 60 which passes the set-screw B'. From this construction it will be seen that when the bar C is to be placed upon the front of the type-writer and in position for use the end having the open slot will be first slipped over the set-screw B³ 65 until the slot c' is above the set-screw B', after which the bar C will be allowed to drop to the position shown in Fig. 1 and the jam-nut B⁴ will be screwed tightly against the bar. Upon the bar C is mounted a sliding carrier, 70 D, which in the construction shown in Figs. 1 and 3 is a chambered block having grooves d and d' to engage with the upper and lower edges of the bar C, and having a cut-away space, d'', from end to end to permit the block 75 D to slide freely over the head of the set-screw B'. Suitable stops, c² and c³, will be placed upon the bar C to limit the movements of the sliding carrier D. This sliding carrier D is provided near its front edge with a vertical 80 perforation adapted to receive the standard E of a suitable copy-holder, F, and a set-screw, G, that passes through a threaded opening in the front of the sliding carrier D, that serves to retain the standard E of the copy-holder at 85 any desired height.

The copy-holder F (shown in the drawings,) is of well-known construction, being preferably provided with a series of clamp-arms, f, adapted to hold a stenographer's book or other 90 manuscript in open position, although it will be readily understood that any other suitable form of copy-holder may be employed. The standard E, that sustains the copy-holder F, is preferably bent, as at e, to enable it to pass 95 freely over the front edge of the machine and at the same time sustain the manuscript or book in close proximity to the carriage of the machine.

From the foregoing description the operation 100 of the form of my invention above described will be seen to be as follows: When

the manuscript or other matter to be copied has been placed within the copy-holder F, the operator will slide the carrier D directly in front of the machine and to a position shown by dotted lines in Fig. 1. In this position the manuscript will be directly in front and over the roll Q of the operator and above the keyboard of the machine, the bent standard E serving to bring the manuscript in close proximity to the carriage J of the machine and to hold it in convenient position to be read. The copy-holder F, while standing directly in front of the traveling carriage of the machine, will not be struck thereby, but the carriage J will be free to move past the copy-holder. When it is desired to lift the carriage, the copy-holder can be moved out of the way by simply sliding the carrier D to the position shown by full lines in Fig. 1, although it is apparent that without departing from the spirit of my invention the copy-holder can be held at sufficient distance in front of the carriage of the machine to permit it to be raised without moving the copy-holder. When the type-writer is to be covered, the bar C can be quickly removed therefrom by loosening the jam-nut B⁴ and then lifting the bar until the screw B' is out of the slot c' and withdrawing the bar from the set-screw B³. It will be readily understood, however, that the precise details of construction of the bar C and its means of attachment to the machine can be varied without departing from the spirit of my invention. If desired, the bar C may be provided near the left-hand side of the machine with a "one-way" hinged joint, C', uniting the two sections of the bar, and with a latch, c⁴, pivoted, as shown at c⁵, so as to swing either in vertical or horizontal position for the purpose of holding the bar rigid or permitting its outer section to be turned upon the hinge. My purpose in providing the bar C with the hinged section is to permit such section to be swung in close proximity to the machine in case it is desired to place the cover of the type-writer upon the machine without first removing the copy-holder attachment.

In the modification of my invention illustrated in Figs. 4 and 5 of the drawings the standard E of the copy-holder is shown as attached rigidly and directly to a bar, H, which in this construction constitutes the sliding carrier for the copy-holder. This sliding carrier H is sustained upon the front of the machine by means of the clamp M, that engages with the post A' of the type-writer, and by means of the clamp N, that is affixed to the opposite post, A. In this modified construction the clamp M has an angular U-shaped portion, m, provided with a threaded perforation to receive a set-screw, O, that bears upon the inner side of the corner-post A' of the machine and serves to securely retain the clamp at the desired position thereon. The outer portion of this clamp M is provided with the outwardly-turned flange m', forming a groove or

way, m², wherein the carrier H can slide, and, if desired, a friction-roller, P, may be journaled at the base of this groove to relieve the friction upon the bottom of the carrier, and a similar friction-roller, P', may be mounted near the top of the clamp to relieve the side friction upon the sliding carrier. The clamp N is similar in construction to the clamp M, except that the latter is by preference provided also with an overhanging flange, m³, that serves to prevent the end of the carrier-bar H from slipping out of the clamp M when the bar H is moved so as to bring the copy-holder to one side of the machine. In this construction the bar H is provided at its end with stops h² and h³ to limit the extent of its movement, the stop h³ being by preference attached by a set-screw, h⁴, which can be readily withdrawn when the bar H is to be removed from the machine.

From the foregoing description the operation of this modified form of my invention will be seen to be as follows: The clamps M and N having been attached in position, the sliding carrier H will be placed upon the clamps. The carrier H can now be moved to the front of the machine in position to enable the operator to readily see the manuscript to be copied, and when it is desired the copy-holder can be moved to one side by merely sliding the bar H toward the left-hand side of the machine, so as to remove the copy-holder from in front thereof. If desired, the sliding carrier H may be provided with a hinged or jointed section similar to the bar C, above described, so as to permit the cover of the machine to be placed thereon without the removal of the carrier.

While I have illustrated what I regard as the preferred forms of my invention, it will be readily understood that without departing from the spirit thereof the skilled mechanic can vary the details of construction set out within wide limits.

Having thus described my invention, what I claim as new, and desire to secure by Letters Patent, is—

1. The combination, with a copy-holder for type-writers, of a sliding carrier whereon said holder is mounted and a suitable support for sustaining said carrier at the front of the machine, substantially as described.

2. The combination, with a copy-holder for type-writers, of a sliding carrier whereon said holder is mounted and a suitable support for sustaining said carrier at the front of the machine, said support comprising clamps for attachment to the front of the machine, substantially as described.

3. The combination, with a copy-holder for type-writers, of a sliding carrier whereon said holder is mounted and suitable supports for sustaining said carrier at the front of the machine, each of said supports having angular portions to receive the corner-post of the machine, and having set-screws for retaining said

supports upon said corner-post, substantially as described.

4. The combination, with a copy-holder for type-writers, of a sliding carrier whereon said holder is mounted and a suitable support for sustaining said carrier at the front of the machine, said carrier being removably mounted upon said support, substantially as described.

5. The combination, with a copy-holder for type-writers, of a sliding carrier whereon said holder is mounted, a suitable support for sustaining said carrier at the front of the machine, and suitable stops for limiting the lateral movement of said carrier, substantially as described.

6. The combination, with a copy-holder for type-writers, of a sliding carrier whereon said copy-holder is mounted, a suitable support for sustaining said carrier at the front of the machine, and a curved standard connecting the copy-holder with the carrier, substantially as described.

7. The combination, with a copy-holder for type-writers, of a suitable bar, C, extending across the front of the machine, suitable supports for sustaining said bar on the machine, and a sliding carrier, D, mounted between said bar and the copy-holder, substantially as described.

8. The combination, with a copy-holder for type-writers, of a bar whereon said copy-holder is mounted, said bar being formed of sections movably connected together, substantially as described.

9. The combination, with a copy-holder for type-writers, of a bar whereon said holder is mounted, said bar being formed of hinged sections, substantially as described.
